[57] CLAIM

The ornamental design for a rotary air compressor, as
shown.

DESCRIPTION

FIG. 1 is a left side elevational view of a rotary air
compressor showing my new design;
FIG. 2 is a right side elevational view thereof;
FIG. 3 is a top plan view thereof;
FIG. 4 is a front elevational view thereof;
FIG. 5 is a rear elevational view thereof; and
FIG. 6 is a perspective view thereof.

Fig. 1.

Fig. 2.
